RACK FOR SUPPORTING COOKED
FRANKFURTERS

Winfred W. Litton, 105 Lake Shore Drive,
Charleston, W. Va.

Filed Sept. 12, 1962, Ser. No. 71,664

Term of patent 14 years

(Cl. D33—3)

FIG. 1 is a top plan view of a rack for supporting cooked frankfurters constructed in accordance with the present design;

FIG. 2 is a front elevation of the rack for supporting cooked frankfurters shown in FIG. 1;

FIG. 3 is a side elevation of the rack for supporting cooked frankfurters shown in FIG. 1;

FIG. 4 is a bottom view of the rack for supporting cooked frankfurters shown in FIG. 1; and

FIG. 5 is a rear elevation of the rack for supporting cooked frankfurters shown in FIG. 1.

I claim:

The ornamental design for a rack for supporting cooked frankfurters, as shown.
